UNITED STATES PATENT OFFICE.

GEORGE J. SCHNEIDER, OF DETROIT, MICHIGAN, ASSIGNOR TO ACME ELECTRIC HEATER COMPANY, OF DETROIT, MICHIGAN, A CORPORATION OF MICHIGAN.

STAND FOR SAD-IRONS.

1,152,767.

Specification of Letters Patent.

Patented Sept. 7, 1915.

Application filed December 8, 1914. Serial No. 876,105.

To all whom it may concern:

Be it known that I, GEORGE J. SCHNEIDER, a citizen of the United States of America, residing at Detroit, in the county of Wayne 5 and State of Michigan, have invented certain new and useful Improvements in Stands for Sad-Irons, of which the following is a specification, reference being had therein to the accompanying drawings.

10 The invention relates to supporting stands for sad irons and consists in the novel construction as hereinafter set forth.

In the drawings: Figure 1 is a side elevation of a portion of a sad iron to which my 15 improvement is applied; Fig. 2 is a longitudinal section therethrough; Fig. 3 is a perspective view showing the stand detached.

My improvement is particularly applicable to sad irons of that type comprising a 20 base section A and a detachable hood B, and with the specific construction shown these parts are locked together by a handle member C, which is provided with a key shank D projecting through an aperture in 25 the hood and engaging a T-slot E in the body of the iron.

My improved stand comprises a substantially U-shaped member F, preferably formed of wire and having its end portions 30 G return-bent at H to form hooks for engaging the rear wall I of the hood. This rear wall is notched at J to provide clearance for the bend in the hook above the bearing of said wall upon the base A.

35 The construction as described may be readily engaged with the hood by slipping the return-bent hooks H upon the wall I and into the notches J thereof, after which the hood is placed upon the base A and is 40 locked in position by turning the handle C. When the hood is thus secured, the stand will be held from disengagement, and by tilting the iron into the position shown in Fig. 1 it will be supported with its heated 45 portion free from contact with the table.

The fact that the bearing of the stand upon the iron is limited to the hook portions H, and the further fact that the heat from the iron must be conducted through the small 50 cross section of wire having a relatively large exposed radiating area, prevents all danger of overheating the stand.

What I claim as my invention is:—

1. The combination with a sad iron provided with a detachable hood, of a supporting stand for said iron having a hooked engagement with the wall of said hood.

2. In a sad iron, the combination with a base section and a detachable hood section having its lower edge in proximity to said base, of a stand having a hooked portion engaging said hood from the lower edge thereof and retained in position by the base portion.

3. In a sad iron, the combination with a base portion and a detachable hood section having its lower edge extending in proximity to the base and notched, of a stand having a hook portion engaging said hood from the lower edge thereof, the bend of said hook passing through said notch and retained by said base.

4. In a sad iron, the combination with a base section and a detachable hood section, of a stand comprising a substantially U-shaped member having return-bent hooks at opposite ends thereof adapted to engage said hood from the lower edge thereof and to be retained in engagement by said base.

5. In a sad iron, the combination with a base section and a detachable hood, of a stand comprising a substantially U-shaped wire member having return-bent hook portions at its opposite ends for embracing the rear wall of said hood, the bends of said hooks engaging notches in the lower edge of said rear wall and being retained by said base.

6. In a sad iron, the combination with a base section and a detachable hood section, of a stand having a hook engageable with the rear wall of said hood when detached from said base, said hook being retained by said base.

7. The combination with a sad iron comprising separable parts, of a stand engageable with one of said parts and retained in engagement by the other part.

In testimony whereof I affix my signature in presence of two witnesses.

GEORGE J. SCHNEIDER.
